UNITED STATES PATENT OFFICE.

LEWIS R. HEIM, OF DANBURY, CONNECTICUT, ASSIGNOR, BY MESNE ASSIGNMENTS,
TO CINCINNATI GRINDERS INCORPORATED, OF CINCINNATI, OHIO, A CORPORA-
TION OF OHIO.

GRINDING DEVICE.

Application filed October 17, 1921. Serial No. 508,125.

This invention relates to grinding devices and with regard to the more specific features thereof to work supports, particularly such as those as are used in machines for 5 grinding cylindrical bodies. One of the objects thereof is to provide a practical device of the above nature of simple and durable construction. Another object is to provide a device of the above nature of exact 10 and dependable action under conditions of hard use. Another object is to provide a work support for a grinding machine of the above character adapted accurately to maintain the desired position of the work 15 throughout long-continued use. Other objects will be in part obvious and in part pointed out hereinafter.

The invention accordingly consists in the features of construction, combinations of 20 elements and arrangement of parts which will be exemplified in the structure hereinafter described and the scope of the application of which will be indicated in the following claims.

25 In the accompanying drawing in which is shown one of various possible embodiments of this invention,

Figure 1 is an end view;

30 Figure 2 is a side elevation of the parts shown in Figure 1, the wheels being dia-
grammatically indicated and certain parts being broken away in order to show the construction more clearly.

35 As best shown in Figure 1 of the drawing, there are provided two abrasive wheels 10 and 11 such as emery wheels driven from any suitable source of power. These wheels rotate as indicated by the arrows in Figure 1 in opposite directions, the wheel 10 turning 40 downwardly where it contacts the work and the wheel 11 upwardly. Also in the preferred use of this invention, the wheel 10 is of many times the speed of the wheel 11 and does substantially the entire grinding. The

45 wheel 11 serves as a regulating wheel, that is it governs the rotation of the work without substantial slip, and also feeds or advances the work in the direction of the arrow thereon in Figure 2 of the drawing. This 50 latter action is brought about by a slight relative inclination between the direction of travel of the work and the direction of travel of the active face of the regulating wheel, whereby the latter exerts a lengthwise thrust

on the work. This angle is relative and 55 either the work or the wheel itself may be inclined with respect to the vertical; the latter arrangement being employed here as indicated in Figure 2. The work here shown at 12 as comprising a series of short cylindrical rolls supported between wheels 10 and 11 is acted upon in accordance with the principles set forth in my patent, Reissue No. 15,035, although various features of the machine are not here shown as they form in 60 themselves no part of the present invention.

Turning now to the work support, which is the part most closely related to my invention, it may here be noted that this comprises a carrier member 13 mounted in any 70 suitable manner in a supporting post 14 for universal adjustment. As here shown it is held in position by a pivot bolt 15 passing through upright slots 16 in the part 14 and a round hole in the carrier member. This 75 arrangement would of course permit of vertical and angular adjustment of the carrier, and lateral adjustment may be gained by any suitable means such as the slot 17 in a flange 18 on the post 14, through which slot a screw 80 19 passes into the frame 20 of the machine. It is to be understood that all of these adjustments are illustrated merely in a dia-
grammatic way.

In the upper portion of the carrier mem- 85 ber 13 there is formed a recess 22 shaped to provide undercut walls 23 and which may extend from end to end thereof. The mem- 90 ber 13 is preferably split into two parts as indicated at 21 in the drawing and may be spread apart or clamped together by bolt 15 to grip the part inserted in its recess, as hereinafter explained. It is to be noted that al- 95 though the recess is shown as extending from end to end of the support, many of the ad- 100 vantageous features of this invention may be achieved in a construction in which the re-cess extends part way only, the member posi- 105 tioned therein being inserted either endwise from one end of the support or by the separa-
tion of the two parts of the support. The shape of recess 22 is subject to considerable variation but it is here shown as an equi-lat-
eral and equi-angular hexagon. It might well be a similarly symmetrical octagon or of other form, and in fact in so far as certain broad features of the invention are concerned its walls might be cylindrical. It should pref-

erably however, possess two characteristics namely, its walls, or one of them, should overhang portions of the recess; and it should be of such form as to permit a wear 5 member 24 positioned therein to be turned or removed and re-inserted with a changed surface exposed. Preferably the wear member 24 fits closely in the recess in which it is positioned, but many of the broader features of my invention may be achieved in a construction in which the wear member does not interlock into the recess against rotation about its own axis and it is merely held from such rotation by the clamping action of the 10 portions of the member 13.

It is also to be noted that although the member 24 may comprise a single continuous part, it is nevertheless advantageous to build it in sections as the parts 24^a, 24^b and 20 24^c. These sections furthermore are preferably interlocked one with another at their ends as by the lugs 25 fitted within corresponding recesses 26, thus holding the parts in exact alignment.

25 This member 24 as above noted is formed of hard or "wear-resisting" material and exposes a wearing surface on which the work rests. In this manner the rotation of the work as it is ground will have only a slight 30 wearing effect on its support and the tendency to wear a groove in the latter with consequent inaccuracy, is considerably reduced. When however the upper surface has become worn it is necessary merely to 35 turn or remove the rod and re-insert it with another one of its faces in active position. As it exactly fits the symmetrical recess 22 it will in all positions be rigidly held in predetermined form, even though it is of 40 light construction, and any tendency of it to spring out of the member 13 is positively prevented. Furthermore a large number of 45 wearing surfaces is attained, and its life as well as the accuracy of its action and adaptability to meet conditions of hard use, are much enhanced. It is also to be noted that even though the hardened member 23 be slightly warped, it will, due to the 50 fact that it is rigidly and firmly locked in position throughout its length, be straightened and held in such straightened condition.

Another feature of importance is that when the sectional form of the part 24 is employed, those sections which are most subject to wear which are positioned immediately between the grinding wheels, may be removed and replaced without the necessity for renewal of the sections which are less worn.

55 It will thus be seen that there is provided a simple and practical construction 60 in which the objects of this invention are achieved.

As various possible embodiments might be made of the above invention and as various changes might be made in the embodiment 65 above set forth, it is to be understood that all matter herein set forth or shown in the accompanying drawing is to be interpreted as illustrative and not in a limiting sense.

70 I claim as my invention —

1. In grinding apparatus, in combination, a work supporting member having a recess throughout its length, and a wear-resisting member fitted into and interlocked with said supporting member substantially 75 throughout its length and adjustable with respect thereto about its longitudinal axis to change the surface exposed for wear.

2. In grinding apparatus, in combination, a work supporting member provided with a recess, and a wear member having the cross-section of the equi-angular polygon fitted in said recess to interlock therewith substantially throughout its length but exposing one of its faces for wear.

80 3. In grinding apparatus, in combination, a work supporting member having a recess extending throughout its length, a wear-resisting member seated within said recess and comprising a plurality of sections 90 arranged end to end and adapted to expose a substantially continuous line of contact to work of round section supported thereon, and means for holding said parts in assembled relation, said sections being interlocked 95 to permit rotation thereof as a unit in said recess.

In testimony whereof, I have signed my name to this specification this 26th day of September, 1927.

LEWIS R. HEIM.
